TROUSER

Lyman B. Cooper, R.D. 1, P.O. Box 56,
Yorktown Heights, N.Y. 10598

Filed Feb. 8, 1971, Ser. No. 113,801

Term of patent 14 years

Int. Cl. D2—02

U.S. Cl. D2—28

FIG. 3

FIG. 2

FIG. 1

FIG. 6

FIG. 5

FIG. 4

FIG. 1 is a front perspective view of a trouser showing my new design, the leg portions being broken away for convenience of illustration, portions not shown being conventional;

FIG. 2 is a view similar to FIG. 1 but showing the trouser in an open position;

FIG. 3 is a rear perspective view thereof;

FIG. 4 is a front perspective view of a second embodiment of the design shown in FIG. 1;

FIG. 5 is a view similar to FIG. 4 but showing the trouser in an open position; and

FIG. 6 is a rear perspective view thereof.

I claim:

The ornamental design for a trouser, substantially as shown and described.
